Specification for Design.

Patented Mar. 7, 1922.

Application filed November 2, 1921. Serial No. 512,381. Term of patent 3½ years.

To all whom it may concern:

Be it known that I, JAMES H. BUNTING, a citizen of the United States, residing at New York, in the county of New York and State of New York, have invented a new, original, and ornamental Design for a Textile Fabric, of which the following is a specification, reference being had therein to the accompanying drawings.

The figure is a plan view of a piece of textile fabric showing my new design.

What I claim is:

The ornamental design for a textile fabric, as shown.

In testimony whereof I hereunto affix my signature.

JAMES H. BUNTING.
